CYLINDER FOR PRINTING MACHINES

Albert J. Horton, White Plains, N. Y., assignor, by
mesne assignments, to R. Hoe & Co., Inc., New
York, N. Y. a corporation of New York

Application December 20, 1934, Serial No. 758,428

12 Claims. (Cl. 101—375)

This invention relates to a cylinder structure which is especially applicable to printing machines of the type used for rotary intaglio printing. In machines of this kind, the form cylinders are removed from the machine in order to prepare them for printing, this procedure being necessary every time the form is changed, and for this reason, it is desirable that the weight of the cylinder be kept to a minimum. In operation, an impression cylinder presses the web against the form cylinder continuously, there being no intermittent relief from pressure as is the case in printing machines which print from plates that are clamped to the cylinder. This pressure causes the cylinders to be deflected along their contact areas, and in consequence less pressure is exerted at a spot in the center of the contact area than elsewhere, the pressure varying from a minimum at the center, to a maximum at the ends. Obviously this variation in impression pressure is objectionable for the best results are attained when the pressure is equal over the entire printing surface.

In the cylinder structure according to the present invention, a certain amount of deflection will occur at the center of the cylinder, but instead of being deflected only at the center, the cylinder herein disclosed is also deflected at both ends. By permitting a deflection of the cylinder at its ends as well as at the center, a condition is produced wherein the contact area of the cylinder will have a slightly waved surface with three low points one at each end and one in the center, but the amount of deflection at the low points is so slight that the resulting surface is practically straight.

When properly proportioned, it is practical to construct a cylinder 15" in diameter having a printing surface six feet long, and wherein the variation between the high and low surfaces referred to will not exceed approximately .001" under operating conditions; whereas in cylinders of the conventional type, the deflection at the center would be at least .007". Furthermore, a printing cylinder made in accordance with the invention will weigh but approximately 60% of the weight of one of the conventional type.

It is the principal object therefore, of this invention, to provide a cast cylinder structure, which when subjected to a pressure equally distributed along its length as under normal operating conditions, will be deflected both at its center and at its ends, in a manner that will tend to produce a substantially straight or undistorted surface.

It is a further object to provide a cylinder struc-

ture which has an inner supporting member preferably cast integral therewith along its central circumferential area and having journals at the ends of said supporting member.

It is also an object of the invention to provide a cast cylinder of generally improved construction, whereby the device will be simple, light, durable and inexpensive in construction, as well as convenient, practical, serviceable and efficient in its use.

With the foregoing and other objects in view, which will appear as the description proceeds, the invention resides in the combination and arrangement of parts and in the details of construction hereinafter described.

The preferred embodiment of the invention is illustrated in the accompanying drawing, wherein:

Figure 1 is a side elevational view of a portion of a typical rotary intaglio printing machine to which a printing cylinder of the type herein disclosed is especially adapted;

Figure 2 is a vertical longitudinal section through a printing cylinder;

Figure 3 is an end elevational view with part 25 broken away, looking in the direction of the arrow 3 of Figure 2; and

Figure 4 is a fragmentary sectional detail showing a modified form of structure with a journal formed as a part of the inner supporting member, 30 and also a modified form of covering for the cylinder ends.

In Figure 1, a rotary intaglio printing machine is shown in which a printing cylinder 11, of the improved type herein disclosed, is mounted. An impression roller 12 is mounted above the printing cylinder 11 and is arranged to apply a substantial pressure against the web W running between the said cylinder and roller, according to the usual practice in printing machines of this type. It is due to the pressure of the impression roller that the printing cylinder is deflected during the printing machine operation.

The detail of the cylinder structure, best shown in Figure 2, comprises an outer cylindrical shell 45 13 and a supporting member or inner shell 14, with said inner member preferably cast integrally with the outer shell along a central circumferential area 15 to thus provide a reinforced centrally supported area on the outer shell and a non-supported area at each end thereof. The two ends 16—16 of the supporting member, which extend beyond each end of the integral or reinforced area, preferably converge inward to a form of truncated cone, and as shown, each has a fluted 55

flanged portion 17 at its outer end, also a bore 18 therethrough. Gudgeons are provided for the ends of the supporting member 14, each of which comprises a plug end 19, a journal end 21, and a flange 22. The plug end 19, of each gudgeon, fits within its respective bore 18, in the ends of the supporting member and the flanges 22 thereon are secured to the fluted flanges 17 by means of screws 23, and thereby provide journals.

10 As thus far described, it will be observed that if these journals 21—24 are supported in suitable bearings not shown, the supporting member 14 will be supported by the bearings, while the outer shell 13 will be supported by the supporting member along a central circumferential area. It will be further observed that the opposite ends of the outer shell will overhang the ends of the supporting member and are thus free to be deflected.

15 When there is an evenly distributed load on the cylinder structure, as for example when another cylinder such as the impression cylinder 12, Figure 1, is in operative engagement with the cylindrical shell of the cylinder structure 11, a deflection at the center of the contact area will occur, but the overhanging ends of the outer shell will also be deflected. Therefore, although there is a deflection at the center of the cylinder structure, the deflection at the ends of the outer shell will offset the central deflection and produce a slightly waved surface along the longitudinal contact area thereof. But, while the said contact area is actually wavy the difference between the low and high wave surfaces will be so slight that the resulting surface will be substantially flat.

20 35 It will be noted that the inner section or shell 14, herein comprising the somewhat thickened wall central area 15 of the shell or outer section 13 and the truncated cone shaped ends 16, forms a longitudinally extending reinforcing truss or arch for the outer section of the shell which may be considered as being supported cantilever-wise and that the natural tendency of the outer section to bend will be opposed by this arched structure.

40 45 When the casting mould is prepared previous to casting the cylinder structure shown in Figure 2, suitable cores are arranged to provide the center cavity 20 and also the end cavities 20a between the supporting member and the outer shell, the cores being properly positioned by supports which form the openings 24 in the supporting member.

50 55 When the casting is completed, the ends of the supporting member, previously referred to as the fluted flange 17, are preferably joined with the ends of the outer shell by ribs or arms as can be visualized from Figure 3, but said arms are later cut to thereby separate the ends of the supporting member from the outer shell. When said arms are cut, the ends of the supporting member are provided with a fluted flanged portion, while the ends of the outer shell are provided with a series of angularly spaced lugs, indicated at 28.

60 65 In preparation of form cylinders used in rotary intaglio printing machines, it is necessary to rotate them in an electro-plating bath to deposit the metal used for the printing surfaces. As herein disclosed, means is provided to close the ends of the cylinder structure to prevent the electro-plating solution from entering the cylinder. This means includes end cover plates 25, which have central clearance openings 26 therein, and fit within the walls of the outer shell 13. The cover plates are secured in position by means of screws 27, which engage the previously described lugs 28 projecting inward from the interior of the outer

shell. The journaled ends of the gudgeons project through the clearance openings 26 in said cover plates and soft rubber or similar packing sleeves 29 are provided to close the clearance openings. Said packing does not interfere with the deflection of the ends of the outer cylinder however, when the cylinder is operating.

70 75 While the cylinder structure has been illustrated in connection with a rotary intaglio printing machine, it will be understood that the same may be used for other purposes, and that the end covering and packing 29 may be omitted if desired.

80 85 In Figure 4, a modified arrangement is shown in which the journals are formed as an integral part of the supporting member, as indicated at 31, thus eliminating the gudgeons. A flexible plate or covering 32 is also shown, secured to a flange 33 on the outer shell 13 and to a flange 34 on the supporting member 14 to provide a means for covering the open end of the cylinder structure. 90 The plate may be made of any elastic material which will not interfere with the deflection of the ends of the outer shell, and is preferably secured in place by rings 35, 36, secured by screws 37, 38, thereby providing a tight joint.

95 100 It can be proven mathematically that a cylinder designed as herein disclosed and having an overall length of the outer shell of 70", a wall thickness at the center of the shell twice as great as the thickness at either end, and the distance between lines A and B approximately 20% of the total length of the shell, will when supported in bearings approximately 30" apart and subjected to a load of 5 tons distributed equally along its upper periphery, be deflected in such manner that the area to which the pressure is applied will not be distorted from a straight surface to a degree in excess of .001". A cylinder so constructed and weighing approximately 1000 lbs. compares very favorably with a cylinder of conventional design 105 which in the same material would weigh 60% more and which would show a deflection at the center of .007" greater than the deflection at the ends when similarly loaded. From these figures, it will be understood that a structure has been 110 provided which is particularly well adapted to printing cylinders that require frequent handling, as a very material saving in weight may be effected and the structure is such that when subjected to loading as encountered in service, there 115 is no appreciable distortion of the contact area and substantially equal pressure throughout the length of the cylinder is maintained, whereas with conventional types of cylinders, difficulty is experienced in obtaining uniformity in the printing due to the lighter pressure that is obtained 120 at the mid section cylinder surface.

125 130 It will be understood that the invention may be embodied in other specific forms without departing from the spirit or essential attributes thereof and it is therefore desired that the present embodiment be considered in all respects as illustrative and not restrictive, reference being had to the claims rather than to the foregoing description to indicate the scope of the invention.

135 What I claim is:

140 1. In a cylinder structure, a cylindrical shell having a supporting member within same, said supporting member being formed integral with the shell and in the form of a longitudinally extending arch constituted by a central circumferential area of said shell and end portions each in the form of a truncated cone, and said shell having its ends overhanging said supporting member.

2. In a cylinder structure, an outer shell, an internal supporting structure in the form of a longitudinally extending arch, the central portion of said supporting structure being constituted by a central portion of said outer shell, end portions on said supporting structure projecting towards the ends of the outer shell, and journals formed on said end portions. 5
3. A reinforced cylinder structure comprising an outer shell and an inner shell, said inner shell being joined to said outer shell and having a central circumferential portion constituted by a central circumferential portion of the outer shell and having its opposite ends converging inwardly toward the axis of said outer shell. 10
4. In a cylinder structure, an outer shell, an inner shell formed integral with said outer shell along a common central circumferential area thereof, extended ends on said inner shell free from engagement with the outer shell and having a central bore at each of said ends. 15
5. In a cylinder structure, an outer shell, an inner shell formed integral with said outer shell along a common central circumferential area thereof, inwardly converging end portions extending an equal distance beyond each end of the said common area, and journals on said extended ends. 20
6. In a cylinder structure, an outer shell, an inner tubular shell formed integral with said outer shell along a central circumferential area thereof, an inwardly converging end portion on said inner shell extending from each end of said common area toward an end of said outer shell, 25 journals formed on said converging ends, a cover plate secured to each end of the outer shell, each cover plate having a clearance opening therein to clear the journals, and a flexible packing sleeve to seal said clearance openings. 30
7. In a cylinder structure, an outer shell, an inner shell formed integral with said outer shell along a common central circumferential area thereof, a truncated cone shaped end extending from each end of said common area, journals 35 provided at the ends of said truncated cones, and flexible means secured to the ends of both the inner and outer shells to close the ends of the outer shell. 40
8. In a cylinder structure, a cylindrical shell 45 interiorly supported cantilever-wise by an inner section integral with said shell at its central portion and in the form of an arch extending longitudinally of said cylindrical shell, said arch form being constituted by a central portion of said shell, and truncated cone shaped end portions each extending from an end of said central portion axially toward an end of said shell, with the small end of the cone shape concentric with said shell end. 50
9. In a cylinder structure, a cylindrical shell 55 interiorly supported cantilever-wise by an inner section integral with said shell at its central portion and in the form of an arch extending longitudinally of said cylindrical shell, said arch form being constituted by a central portion of said shell, and truncated cone shaped end portions each extending from an end of said central portion axially toward an end of said shell with the small end of the cone shape concentric with said shell end, and means at the small end of each of said cone shaped end portions adapted to rotatably support said shell. 100
10. In a cylinder structure, a cylindrical shell 60 interiorly supported cantilever-wise by an inner section integral with said shell at its central portion and in the form of an arch extending longitudinally of said cylindrical shell, said arch form being constituted by a central portion of said shell, and truncated cone shaped end portions each extending from an end of said central portion axially toward an end of said shell with the small end of the cone shape concentric with said shell end, a member secured to the small end of each of said cone shaped end portions for rotatably supporting said shell, said members extending beyond the end of said shell, and a disc secured at its periphery to each end of said shell and through which said member protrudes. 15
11. In a cylinder structure, a cylindrical shell 65 supported cantilever-wise by an inner section in the form of an arch extending longitudinally of said shell, said arch form having end portions converging inwardly and extending axially of said shell, and a common central cylindrical portion 20 for said shell and the arch form of said inner section. 25
12. In a cylinder structure, a cylindrical shell 70 having a centrally disposed thickened wall portion, said shell being supported cantilever-wise by an inner section in the form of an arch extending longitudinally of said shell, said arch form having end portions converging inwardly and extending axially of said shell, said central thickened wall portion of said shell forming a central portion for said inner section from the ends of which said converging end portions extend. 40
